FOLDING MECHANISM

Clarence J. Malhiot, Oak Park, Ill., assignor to
F. B. Redington Co., Chicago, Ill., a corporation
of Illinois

Application June 29, 1940, Serial No. 343,115

19 Claims. (Cl. 93—2)

This invention relates to folding mechanism in general, and particularly to folding mechanism for wrapping machines, and its primary object is the provision of new and improved folding mechanism for folding a wrapper or circular wholly or partially about an article while the article is continuously moving at a predetermined speed along a conveyor.

Another object of the invention is the provision of continuously operating folding mechanism comprising relatively few and simple parts for folding over a circular or wrapper about one or more surfaces of a continuously moving article.

A further object of the invention is to provide improved folding mechanism comprising relatively few and simple parts, each of which is continuously moving in proper synchronism to fold effectively a circular or wrapper about a continuously moving article in a predetermined manner.

A still further object is to provide folding mechanism which will encase, wrap, or encircle a continuously moving article and maintain the wrapper or circular about the article until the article is deposited in a carton, whereby the circular or wrapper containing printed instructions or other matter must be withdrawn with the article from the package.

Still another object is the provision of folding mechanism which is efficient and positive in operation, which is rigid and durable in construction, which can be readily and economically manufactured and assembled, and which is not likely to get out of order.

Numerous other objects and advantages will be apparent throughout the progress of the following specification.

The accompanying drawings illustrate a selected embodiment of the invention and the views therein are as follows:

Fig. 1 is a detail top plan view of the improved machine;

Fig. 2 is a detail longitudinal sectional view on the line 2—2 of Fig. 1;

Fig. 3 is a detail longitudinal sectional view on the line 3—3 of Fig. 1;

Fig. 4 is a detail transverse sectional view on the line 4—4 of Fig. 1;

Fig. 5 is a detail sectional view on the line 5—5 of Fig. 1;

Fig. 6 is a view similar to Fig. 5 but showing certain parts in advanced position;

Fig. 7 is a detail sectional view on the line 7—7 of Fig. 6;

Fig. 8 is a view similar to Fig. 7 but showing the folder in advanced position;

Fig. 9 is a perspective view of a circular or wrapper partly folded about an article; and

Fig. 10 is a perspective view showing the wrapper or circular completely folded about the article.

The particular machine herein disclosed for the purpose of illustrating the invention comprises a suitable base or supporting frame 1 upon which there is operatively supported a prime mover, such as an electric motor (not shown). A conveyor 2, in the form of spaced buckets or pockets 3 pivotally connected at 4 by means of chain links 5, passes over sprockets 6 which are mounted on each end of the frame, Fig. 4. One of the sprockets 6 is operatively connected to and driven by the prime mover continuously and uniformly at a pre-selected speed, while the other sprocket 6, Fig. 4, is merely an idler sprocket.

A circular or wrapper 7 is adapted to be arranged between the side walls 8 of the pocket or bucket members 3 and folded around or about articles 9 which are later packaged in cartons.

The circular or wrapper 7 is first applied in position in the bottom of each pocket or bucket 3, the article about which the circular or wrapper is to be folded being first placed on top of a previously positioned circular or wrapper. The circular or wrapper 7 which is to be folded about the article, or in which the article is to be wrapped, extends a predetermined distance beyond an end of the bucket or pocket 3, as indicated at 1a, Figs. 1 and 4. The positioning of the circular or wrapper is such that one of its longitudinal edges will be substantially flush or immediately adjacent a side wall 8 of the pocket, Fig. 1.

The circular or wrapper 7 which is moving toward a predetermined folding position passes below the under side of a guide member 10, Fig. 1, which tends to keep it from raising out of the pocket. A longitudinally extending guide bar 11, Figs. 1 and 3, rigidly secured to a part of the frame 1, inclines in the direction shown in Fig. 3, and its purpose is to engage the under side of the free overhanging part 1a of the circular or wrapper to hold it up in a predetermined horizontal plane substantially in line with the supporting surface of the bucket or pocket 3. Therefore, as the circular or wrapper 7 moves toward folding position, it is held in the pocket properly and prevented from raising out of the pocket member 3 by the guide member 10 and the guide bar 11. The circular or wrapper,

therefore, is maintained in proper position to be engaged or acted upon by suitable mechanism to perform the folding or wrapping operation.

When the wrapper or circular 1 has reached a predetermined position, the free end 1a thereof is engaged by a rotary folding member 12. This folding member 12 comprises a relatively straight folding finger 13 which is integrally connected with a stem part 14, the finger 13 being relatively at right angles to the part 14, Figs. 1, 2, and 7.

The stem or supporting portion 14 of the folding member 12 is rigidly secured to a collar 15 which is rigidly secured at 16 to a shaft 17, Figs. 1, 5, and 6. The shaft 17 is operatively mounted in a supporting bracket 18 which acts as a bearing therefor, being driven by a sprocket 19, Fig. 1, secured to the opposite end of the said shaft 17. The sprocket 19 may be driven by a sprocket chain 20 from a driving sprocket 21 mounted on a sprocket shaft 22, Fig. 4. The sprocket shaft 22 is synchronized and correlated with the mechanism which operates the conveyor 2, whereby the folding member 12 operates in proper timed relationship with the pockets or buckets 3 as they arrive at a predetermined position.

The finger 13 engages the under side of the overhanging part 1a of the wrapper or circular 1 and raises it upwardly out of the normal flat position shown in Fig. 1, to the vertical positions shown in dotted and full lines in Fig. 5. The finger 13 operates outside of the guide member 10 which also acts as a breaker rod or bar to cause a relatively sharp or neat fold to be made in the circular or wrapper 1, Fig. 5. As the folding member 12 moves to a predetermined position, the part 1a of the circular or wrapper, which is now upstanding as shown in Fig. 5, is engaged by a constantly driven rotary folder 23.

The folder 23, which has a thickened face 24, is relatively segment-shaped and rotates to a predetermined position to fold the upstanding free end of the circular or wrapper down against the upper surface of the article 9. The folder face 24 of the folder 23 comprises an arcuate member adapted to engage the now upstanding part of the circular or wrapper and fold it against the top of the article 9. The member 23 is so constructed that the peripheral surface 25 of the folder face 24 extends between the upstanding sides 8 of the buckets or pockets 3 and below the upper ends thereof to insure the circular or wrapper being located properly, Fig. 7. This peripheral surface 25 holds the free folded-over end of the wrapper or circular below a predetermined position so that it may ride under a stationary guide bar 26, Figs. 1 and 2.

The stationary guide bar 26 is rigidly secured to a part of the frame and extends longitudinally a predetermined distance from folding position toward discharging position. This guide bar keeps the wrapper or circular in relatively close contact with the article. The side walls 8 of the buckets or pockets 3 are provided with notches or cut-outs 21, Figs. 1 and 8, to permit the pockets to pass freely under the stationary guide bar 26. The purpose of the stationary guide bar 26 being set downwardly a predetermined distance into the buckets or pockets 3, is to prevent the upper folded portion of the circular or wrapper from dragging in a rearward direction, and preventing it from canting, skewing or becoming otherwise misplaced.

The folder 23, which is in the form of a segment as clearly shown in Figs. 4-6, includes a web or end support 28 rigidly secured to a hub 29

rigidly fastened to a shaft 30. The shaft 30 is mounted in a suitable bearing 31, Figs. 1 and 2, secured to a part of the machine frame, driven by a sprocket 32. The sprocket is operated by a sprocket chain 33 driven from a driving sprocket 34 on the shaft 22, Fig. 1. A transverse slot 35, Figs. 2 and 3, of appreciable width is provided in the folder to permit the passage of the finger 13 of the folding member 12 through the folder during the operation of those two elements.

The folder face 24 of the member 23 is of appreciable length and extends from one end of the segment completely to the other end as shown. This face 24 is relatively wide at 36 where the folding surface 25 first engages the circular or wrapper, Figs. 1, 2, and 7. The part 36 is slightly less in width than the distance between the legs 8 of the pockets 3, Fig. 7. One edge of the folder face 24 is made spiral, as indicated at 37, Figs. 2 and 3, so as to maintain the surface 25 in engagement with the circular or wrapper for an appreciable length of time during the continuous movement of the conveyor. The spiral edge 37, therefore, permits relatively long contact of the surface 25 with the circular or wrapper within the side walls 8 of the pockets or buckets 3 during the continuous travel of the conveyor 2. The face 24 reduces in width from its first engaging edge 36 to a relatively narrow part 38 at its extreme opposite end where it ceases its engagement. The engaging surface 25 therefore stays in contact with the circular or wrapper for a length of time sufficient to permit a pocket 3 to move to a predetermined position where the circular or wrapper is guided under the stationary guide bar 26.

The circular or wrapper is insured of being maintained in proper position in the pocket or bucket 3 by the use of a squaring member 39 which is rotatively mounted adjacent the folding mechanism, Figs. 1 and 4. This squaring mechanism includes an upstanding blade 40 which is adapted to re-locate or shift any misaligned circular or wrapper in a bucket or pocket 3. This rotary squaring member is adapted to move to operative position just immediately prior to the time at which the folding pin 13 engages the overhanging portion of the circular or wrapper to raise it a predetermined distance. The finger 13 holds the circular or wrapper upwardly a predetermined distance during the continued advance movement of the rotary squaring blade 40 so as to move the circular or wrapper out of the path of the blade immediately after it has squared or aligned the circular and immediately before engagement of the finger 13. Therefore, because the finger 13 has raised the free end of the circular or wrapper up a predetermined distance during the advance movement of the squaring blade 40, the squaring blade is prevented from further contacting the circular or wrapper, thereby preventing mutilation, damage or shifting of the circular or wrapper by the blade 40 after it has performed its intended object or purpose.

The squaring member 39 comprises the relatively square upstanding blade 40 which is operatively connected at 41, Fig. 1, to a rotary mounted shaft 42. The shaft 42 is cut away to provide a relatively straight surface 43 against which the squaring blade 40 is suitably attached by fastening means such as screws 44. The shaft 42 is suitably mounted in bearings 45 and 46 operatively secured to the machine frame, Fig. 1.

The shaft 42 is driven by means of intermeshing bevel gears 47 and 48 operatively mounted

on the shaft 42 and on another shaft 49, respectively. The shaft 49 carries a sprocket 58 over which is run the previously mentioned sprocket chain 33, Figs. 1 and 4. Tightener sprockets 51 and 52, Fig. 4, may be provided for the sprocket chains 20 and 33, respectively.

A circular or wrapper 7 may completely encircle the article instead of merely folding the wrapper or circular in the form of a U. Both ends of the wrapper or circular may be folded about the article by employing duplicate mechanism 60, Fig. 4. This mechanism 60 is a duplication of the previously described folding mechanism and includes an additional guide bar 10, guide member 11, folding member 12, folder 23, 15 and squaring member 38. The mechanism 60, which comprises the addition of the elements just described, may be removed from the first described elements and located at the position shown in dotted lines in Fig. 4. The previously described mechanism and the duplicating mechanism 60 may fold over both the ends of the circular or wrapper. When both ends of the circular or wrapper 7 are to be folded over, the circular or wrapper is positioned in a bucket or pocket 3 so that a part 7a will extend a predetermined distance from each end of the bucket or pocket. One extending end 7a will be folded over by the mechanism just described, while the other end 7a will be folded over by the duplicate mechanism. Therefore, it can be readily understood from an examination of the drawing and the specification, that both ends of the circular may be folded over against the article by a mere duplication of the previously described mechanism.

Moreover, the invention contemplates the described mechanism, or a duplication thereof, for completely wrapping a wrapper about the article. In Figs. 9 and 10 there is shown a wrapper 7 having one end section 7a extending a predetermined distance out of the pocket, with the guide bar 10 in position. The other free end 7b extends a predetermined distance beyond the article with a second guide bar 10b in engagement therewith. The previously described mechanism will fold the free end 7a over in the position shown in Fig. 10, while the duplicate mechanism will fold the free end 7b about the guide bar 10b. The wrapper 7 may be previously folded longitudinally about the article before it arrives at the folding position.

The invention therefore contemplates folding mechanism which is adapted to fold one or more ends of a circular or wrapper, the ends of which extend freely beyond the edges of the pockets or buckets. The invention also provides mechanism for completing the folding, whether it be one end or both ends of the article, or whether the article is completely folded within a wrapper or encircled therewith. The mechanism for effecting the folding operation is relatively simple but positive and effective. The entire folding mechanism is economical to manufacture and apply to a machine and is adapted to perform efficiently the function for which it is intended.

Changes may be made in the form, construction and arrangement of the parts without departing from the spirit of the invention or sacrificing any of its advantages, and the right is hereby reserved to make all such changes as fairly fall within the scope of the following claims.

The invention is hereby claimed as follows:

1. Folding mechanism for folding a wrapper such as a circular or the like about an article and

comprising a support for supporting and advancing an article and wrapper past a folding position, the wrapper extending a predetermined distance beyond a predetermined supporting part of the support, a continuously rotating finger movable to raise the extending portion of the wrapper to a predetermined position, and a continuously rotating folder coordinated with the movement of said finger and engageable with the wrapper when in said predetermined raised position to fold the wrapper toward the article.

2. Folding mechanism for folding a wrapper such as a circular or the like about an article and comprising a continuously moving support for supporting and advancing an article and wrapper past a folding position, the wrapper extending a predetermined distance beyond a predetermined supporting part of the support, a continuously rotating finger coordinated to the movement of said support providing for raising the extending portion of the wrapper to a predetermined position, a continuously rotating folder coordinated with the movement of said support and said finger and engageable with the wrapper when in said predetermined raised position to fold the wrapper toward the article, and a member above the support to hold the wrapper in said last named position.

3. Folding mechanism for folding a wrapper such as a circular or the like about an article and comprising a support for supporting and advancing an article and wrapper, the wrapper extending a predetermined distance beyond a predetermined supporting part of the support, means spaced from said part of said support to support the overhanging free end of said wrapper, a finger extending substantially parallel with said last named supporting means and engageable under the overhanging portion of said wrapper to lift the free end of said wrapper to a predetermined raised position, means to rotate said finger, and a folder engageable with the free end of said wrapper when in lifted position to fold the said free end toward the upper surface of the article.

4. Folding mechanism for folding a wrapper such as a circular or the like about an article and comprising a support for supporting and advancing an article and wrapper, the wrapper extending a predetermined distance beyond a predetermined supporting part of the support, means spaced from said part of said support to support the overhanging free end of said wrapper, a finger rotatable about an axis substantially parallel with said last named supporting means for engaging under the overhanging portion of said wrapper to lift the free end of said wrapper to a predetermined raised position, means to rotate said finger, a rotatable folder engageable with the free end of said wrapper when in lifted position to fold the said free end toward the upper surface of the article, means to move the support continuously, and means to rotate the finger and folder continuously and synchronously in timed relationship with the movement of the support.

5. Folding mechanism for folding a wrapper such as a circular or the like about an article and comprising a support for supporting an article and wrapper, the wrapper extending a predetermined distance beyond a predetermined supporting part of the support, means spaced from said part of said support to support the overhanging free end of said wrapper, a finger to lift the free end of said wrapper to a predetermined raised position, a rotatable shaft to which the finger is mounted, a folder member adjacent the finger, a

shaft mounted in a plane parallel to the first shaft and to which the folder member is fastened for rotation therewith, and means to rotate both said shafts simultaneously, said folder member having a slot therein through which said finger passes during rotation.

6. Folding mechanism comprising a continuously moving conveyor carrying an article and a wrapper to be folded about the article, a continuously revolving member arranged in predetermined fixed position along the path of said conveyor to fold the wrapper to a predetermined position as the article is advanced past said member, and continuously rotatable means arranged in fixed position adjacent said member and engageable with the predetermined folded part of the wrapper to fold the wrapper against the article.

7. Folding mechanism comprising a continuously moving conveyor carrying an article and a wrapper to be folded about the article, a continuously revolving member to fold the wrapper to a predetermined position, continuously rotatable means engageable with the predetermined folded part of the wrapper to fold the wrapper against the article, and means engageable with the wrapper to hold the wrapper against the article during continued movement of the conveyor.

8. Folding mechanism comprising a continuously moving conveyor carrying an article and a wrapper to be folded about the article, a continuously revolving member arranged in predetermined fixed position along the path of said conveyor to fold the wrapper to a predetermined position as the article is advanced past said member, a second constantly revolving member arranged in fixed position adjacent said first member and engageable with the wrapper to fold the wrapper from said predetermined position to a position against the article, and means for coordinating the rotation of said first and second revolving members with said continuous movement of said conveyor.

9. Mechanism for folding a wrapper or the like about an article comprising a constantly moving conveyor adapted to carry a wrapper, a part of which overhangs an edge of the conveyor, a finger moving in an orbit engageable with the overhanging end of the wrapper to fold the free end to a predetermined position, a member to square out-of-positioned wrappers into proper position prior to engagement of the finger with the wrapper, a rotary folder adjacent the finger to fold the wrapper after the free end of the wrapper has been moved to said predetermined position, and a stationary guide bar in juxtaposition with respect to the conveyor to hold the folded wrapper in folded position on the conveyor.

10. Mechanism for folding a wrapper or the like about an article comprising a constantly moving conveyor adapted to carry a wrapper, a part of which overhangs an edge of the conveyor, a bar under the free end of the wrapper to support the same, a breaker bar adjacent the conveyor and overlying the wrapper, a finger moving in an orbit engageable with the overhanging end of the wrapper to fold the free end to a predetermined position about the breaker bar, a member to square out-of-positioned wrappers into proper position prior to engagement of the finger with the wrapper, a rotary folder adjacent the finger to fold the wrapper after the free end of the wrapper has been moved to said predetermined position, and a stationary guide

bar in juxtaposition with respect to the conveyor to hold the folded wrapper in folded position on the conveyor.

11. Folding mechanism comprising a substantially cylindrical rotary member, a projection on the outer cylindrical surface of said member having at least one of its sides spiralling, and a longitudinally extending slot in said rotary member and projection for receiving a cooperating folding member.

12. Folding mechanism comprising a rotary shaft, a finger substantially parallel to the shaft and connected to said shaft, a second rotary shaft adjacent the first shaft and located in a plane parallel thereto, a slotted drum on the second shaft, and means for moving the finger through the slot in the said drum during each revolution of the rotary member and drum.

13. Folding mechanism comprising a rotary shaft, a finger substantially parallel to the shaft and connected to said shaft, a second rotary shaft adjacent the first shaft and located in a plane parallel thereto, a slotted drum on the second shaft, means for moving the finger through the slot in the said drum during each revolution of the rotary member and drum, and a projection on said drum having one side straight and one side tapering.

14. Mechanism of the class described comprising a plurality of interconnecting moving buckets forming a continuous moving conveyor, a rotary folder adjacent the conveyor, and a peripheral projection on the folder and extending between the sides of each bucket when the buckets arrive at a predetermined position.

15. Folding mechanism for folding a wrapper about an article comprising a cylindrical member having a peripheral projection, and a conveyor having sides and movable under the cylindrical member, said projection adapted to extend between the sides a predetermined distance during movement of the conveyor.

16. Mechanism of the type described comprising a movable conveyor having a plurality of transversely upstanding spaced sides, a rotary folding member arranged above the conveyor, and a peripheral projection on the said member forming a helical shoulder extending between said sides whereby the projection will remain between the said sides for an appreciable length of time during movement of the conveyor.

17. Folding mechanism comprising a plurality of open-end buckets, each having upstanding sides, links between said buckets and pivotally connected thereto to form an endless conveyor, means to move the conveyor constantly and at a predetermined speed, said buckets adapted to support a wrapper with a part of the wrapper extending beyond an end of the bucket, a guide to support the extended end of the wrapper, a breaker bar adjacent a side of the conveyor, means to shift a misplaced wrapper to a predetermined position in each bucket, a folding member movable in an orbit to fold the wrapper upwardly at the breaker bar, a rotary folder adjacent the folding member to fold the said upwardly extending part of the wrapper downwardly in a plane parallel with the base of the bucket, a peripheral helical rib on the rotary folder adapted to extend between the upstanding sides of the bucket and in engagement with the wrapper to hold the wrapper down in said plane for an appreciable length of time during movement of the bucket, and a stationary guide bar under which the fold-

ed wrapper passes and engages during movement of the conveyor.

18. The method of folding wrappers or circulars about continuously moving articles which consists in placing the wrappers or circulars in spaced relationship on a continuously moving supporting surface with a substantial part thereof overhanging an edge of the surface a predetermined distance, laying articles to be wrapped on top of the wrapper or circular, thereafter adjusting the position of said wrappers or circulars to effect proper folding, then raising the overhanging part to a substantially vertical plane, and finally folding the said vertically extending part downwardly against the body of the article. 15

19. Folding mechanism comprising a guide member for supporting the under side of an overhanging end of a wrapper or the like, a breaker bar extending substantially parallel with said 5 guide member in spaced relation thereto and adapted to engage the upper side of said wrapper, a rotary shaft extending substantially parallel with said guide member and said breaker bar, and a finger substantially parallel to the shaft and connected to said shaft for engaging under said overhanging portion of the wrapper between said guide member and said breaker bar to fold the wrapper about the breaker bar.

CLARENCE J. MALHIOT.
